[57] CLAIM

The ornamental design for an ice skate blade, as shown and described.

DESCRIPTION

FIG. 1 is a perspective view of an ice skate blade showing my new design;

FIG. 2 is a side elevational view thereof, the side opposite being substantially a mirror image;

FIG. 3 is a side elevational view of a second embodiment of the design shown in FIGS. 1 and 2;

FIG. 4 is a bottom plan view thereof;

FIG. 5 is a front elevational view of the design shown in FIGS. 1 and 2;

FIG. 6 is a rear elevational view thereof; and

FIG. 7 is a top plan view thereof.
